BOX

Louis Rosenfield, Brooklyn, N. Y., assignor to Miro Container Company, Inc., Brooklyn, N. Y., a corporation of New York

Application September 20, 1948, Serial No. 148,669

Term of patent 14 years

(Cl. D58—12)

To all whom it may concern:

Be it known that I, Louis Rosenfield, a citizen of the United States, residing in Brooklyn, county of Kings, and State of New York, have invented a new, original, and ornamental Design for a Box, of which the following is a specification, reference being had to the accompanying drawing, forming part hereof.

The single figure of the drawing is a perspective view of a box, showing my new design.

I claim:

The ornamental design for a box, as shown.
LOUIS ROSENFIELD.
